CLAIM

I claim the ornamental design for a magnet embedded bracelet, as shown and described.

DESCRIPTION

A bracelet, band, or the like made of a transparent or translucent material, clear or colored, is embedded with two or more elongated members, which are opaque or a contrasting translucent color, that extend radially around the bracelet and are visible through the material. Preferably the elongated members are magnets that are cylindrical and oriented as shown.

FIG. 1 is a perspective view of a magnet embedded bracelet of my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
